SAFETY DEVICE FOR PRINTING PRESSES

Application filed February 29, 1928. Serial No. 258,049.

My invention relates to that class of devices that are used to prevent injury to an attendant in the operation of printing presses, and an object of my invention, among others, is the production of a safety device that shall be simple in construction, that may be readily applied to printing presses already in use, and that shall be particularly efficient in its method of operation.

10 One form of device embodying my invention and in the construction and use of which the objects herein set out, as well as others, may be attained, is illustrated in the accompanying drawings, in which—

15 Figure 1 is a view in side elevation of a printing press of ordinary construction equipped with my improved safety device.

Figure 2 is a detail view, scale enlarged, on a plane denoted by the dotted line 2—2 of Figure 1.

Figure 3 is a view similar to Figure 1, but with parts broken away to illustrate my improved attachment.

20 Figure 4 is a view similar to Figure 3, but showing the parts of the press substantially in position for a printing impression.

Figure 5 is a detail view of a portion of the structure shown in Figure 4, and illustrating the operation of my improved attachment.

25 Figure 6 is an isometric view, scale enlarged, illustrating the construction and operation of my improved safety device, the parts being substantially in the position shown in Figure 5.

Figure 7 is a view similar to Figure 4, but illustrating the operation of the attachment.

Figures 8 and 9 are detail sectional views, scale enlarged, on a plane denoted by the dotted line 9—9 of Figure 7.

Figure 10 is a detail view in side elevation of the trip device and looking from a point located at right angles to the point of view of Figures 8 and 9.

30 My improved safety device is designed for application to a printing press of ordinary construction and is, in fact, an attachment for the automatic operation of parts heretofore only manually controlled. Such a printing press is shown in the accompanying

drawings in which the numeral 5 indicates the frame as a whole having the usual operative parts supported thereon and which include a main shaft 6 driven as by means of a pulley and belt in an ordinary manner, a fly wheel 7, a swinging bed-plate frame 8 supporting a bed-plate 9 carrying the type, and a platen frame 10 carrying a platen 11. In the particular type of press herein illustrated both the platen and bed-plate have reciprocating movements with respect to each other. The construction and operation of the mechanism for effecting this purpose is well understood by those skilled in the art and for this reason a detailed description of such construction and operation of the press mechanism is omitted herein, except to remark that the bed-plate frame 8 is operated by crank rods or pitmen 12 pivotally connected at each end to opposite sides of the bed-plate frame and to crank discs 13 secured to opposite ends of a shaft 14 suitably connected as by a gear and pinion with the main shaft 6. The platen frame 10 is operated in the usual manner. An inking frame rod 15 is pivotally attached at one end to the frame of the machine and at its opposite end to the side of an inking frame 16 and operated in a manner that will be readily understood.

35 In machines of this kind means are provided to prevent printing under certain conditions, as when a sheet of paper has been improperly placed on the platen, and this is accomplished by mounting the pitmen or crank rods 12 on eccentrics 17 located at the ends of a releasing shaft 18 mounted for oscillating movement in the bed-plate frame 8. This shaft 18 is manually operated as by means of a handle lever 19 pivotally mounted on the frame 5 and having a handle 20 located in convenient position for access to the operator of the machine. This connection comprises a rod 21 pivotally attached at its opposite ends to the lever 19 and to a lever 22 pivotally mounted on the frame 5 and comprising an arm to which the rod 21 is attached, a pivot extending through a side part of the frame and a second arm on the opposite side of the frame from the first, said second arm having a pin 23 engaged in a slot in

one arm of a lever 24 pivotally mounted in the frame 5 and having a second arm to which an actuating rod 25 is pivotally attached. The other end of said rod 25 is pivotally attached to an actuating finger 26 projecting from the releasing shaft 18. The lever 22 has stop fingers 27 positioned to engage a stop pin 28 constituting a projecting end of the pivot for the lever 24 to limit swinging movement of the lever 22.

All of the parts thus far described are of old and well known construction and except in connection with other parts now to be described form no part of my present invention, it being understood that when the handle lever 19 is moved from the position shown in Figure 1 to the position shown in Figure 7, the eccentrics 17 will be rotated from the position shown in Figures 2 and 3 to the position shown in dotted lines in Figure 7, thereby moving the bed plate backward relatively to the crank disc 13 and thereby preventing close approach of the bed 9 and platen 11, and as illustrated in Figure 7.

In carrying my invention into effect I provide a trip rod 29 that is pivotally connected at one end with the bed-plate frame 8 and at its opposite end passes through a trip case 30 attached to and projecting from an actuator 43 to be more particularly hereinafter described, and as illustrated in Figure 6 of the drawings. Said case 30 contains a spring actuated trip stop 31 having a beveled end forced by said spring toward the trip rod 29 and adapted to engage a recess 32 therein.

In the reciprocating movements of the frame 8 the rod 29 plays back and forth through its opening in the case 30, and the stop 31 is held from moving into the recess 32 by a retaining latch 33 pivotally supported by the actuator 43 and connected by a trip actuating rod 34 with a tripping rod 35 at the upper end of the latter, the end of the rod 34 being supported in an opening in a bolt head or support 36, and as shown in Figure 6 of the drawings. The lower end of the rod 35 is pivotally attached to one arm of a trip actuating lever 37, the opposite arm of said lever being connected by a link 38 with one end of a spring actuated trip lever 39 pivotally supported on a bracket 40 secured to the side of the frame 5. The upper end of the lever 39 is connected by a link 41 with a controlling lever 42 pivotally attached to said link and to the bracket 40 and acting to maintain the horizontal position of parts.

A tripping tongue 44 is pivotally supported on the link 41 and in the path of movement of a tripper 45 rigidly secured to one branch 46 of a tripping frame, which frame comprises a contactor 47 in the form of a plate extending across the upper edge of the platen 11, there being a branch 46 rigidly secured at each end of the contactor and extending downwardly along the ends of said platen,

these branches 46 being pivotally attached to the lower edge of the platen frame 10.

In the normal operation of the machine the tripper 45 passes from a position above the tongue 44, which is its position when the machine is ready for insertion of a sheet of paper, in a circular path downwardly to a position below said tripping tongue, the ends of the tripper and tongue, in this operation, contacting with one another, and forcing the contactor 47 to the position shown by dotted lines in Figure 5, thus covering the space between the platen and bed-plate at the time when said parts are approaching each other and preventing an attendant from placing his hands in this space, as for the purpose of retrieving a misplaced sheet of paper. This movement of the tripper 45 downwardly in a circular path from a position above the tongue 44, shown in Figs. 1 and 3, to a position below the tongue 44, as shown in Fig. 4, is accomplished due to the fact that the tripper 45 is mounted on the frame 46 of the contactor 47, the said frame 46 being secured to the platen frame 10. This circular downward movement therefore occurs simultaneously with the movement of the platen frame 10 from a substantially horizontal position, as shown in Fig. 3, to a substantially vertical position in engagement with the bed plate 9 which has been pivoted toward the advancing platen frame by movement of the bed plate frame 8. In the return movement of the parts the tripping tongue 44 turns on its pivot and allows the tripper 45 to pass it, and the contactor 47 is returned to its normal position by striking against the bed-plate 9, or by any other suitable means.

In this printing movement of the parts just described, should the attendant place his hand between the bed-plate and platen, as for the purpose of retrieving a misplaced sheet of paper, and before said plate and platen have closed sufficient to prevent this, as illustrated in Figure 7, the pressure of the forearm against the edge of the contactor 47 will hold the latter from forward movement with a result that the tripper 45 striking the upper part of the tongue 44 will force the latter backwardly, thus swinging the lever 39 on its pivot and operating the trip actuating lever 37 to push the trip rod 35, and consequently the actuating rod 34, upwardly. This lifts the retaining latch 33 from engagement with the trip stop 31, allowing the latter to move inwardly under the influence of its spring. As the trip rod 29 now moves forwardly said stop 31 enters the recess 32 and contacts with the shoulder of said recess. The continued movement of the rod 29 now moves the case 30 and the actuator 43 thus swinging said actuator on its pivotal support at its upper end and moving its lower end toward the front of the machine and this through the connection of the actuator by the

strap 48 with the rod 21 operates the eccentrics 17 as hereinbefore described, thus preventing the platen and bed-plate from closing sufficient to injure the hands located between them.

It will be noted that the actuator 43 serves and operates the regular safety mechanism which, as herein set out, is comprised in printing presses as heretofore made.

10 The eccentric as shown herein comprises a projecting stud eccentrically positioned on the end of the shaft 18 and an eccentric sleeve on said stud. The parts are thus arranged in order to adapt my attachment to presses in common use, but it will be understood that this eccentric may be composed of a single piece if desired.

15 In accordance with the provisions of the patent statutes I have described the principles of operation of my invention, together with the device which I now consider to represent the best embodiment thereof; but I desire to have it understood that the device shown is only illustrative and may be carried out by 20 other means and applied to uses other than those above set out.

I claim—

1. In combination with the relatively movable bed and platen of a printing press together with mechanism including an eccentric for varying the degree of approach of said parts one toward the other and an actuating lever pivoted on a portion of the frame of the press and connected to the eccentric, a contactor relatively movably supported upon one of said parts, a connection between said contactor and the actuating lever of said mechanism to effect, by reason of movement of said contactor on its support, operation of 25 said eccentric to increase the distance between said parts at their nearest approach, and means for disconnecting said connection to permit movement of said actuating lever independently of said mechanism.

2. In combination with the relatively movable bed and platen of a printing press together with mechanism for varying the degree of approach of said parts one toward the other, a contactor relatively movably supported on one of said parts, a movably mounted actuator connected with said mechanism to effect its operation, a trip rod loosely engaged with said actuator, means for imparting movement to said trip rod simultaneously with the movement of one of said parts, means for rigidly connecting said trip rod with said actuator, a connection between said contactor and said connecting means to effect said rigid connection, and 30 means for disconnecting said connection to permit movement of said actuating lever independently of said mechanism.

3. In combination with the relatively movable bed and platen of a printing press together with mechanism for varying the de-

gree of approach of said parts one toward the other, a contactor relatively movably supported by said platen, a movably mounted actuator connected with said mechanism to effect its operation, a trip rod loosely engaged with said actuator for movement independently thereof and connected with one of said parts for simultaneous movement therewith, means for rigidly connecting said trip rod with said actuator, and a connection between said contactor and said connecting means to effect said rigid connection.

4. In combination with the relatively movable bed and platen of a printing press together with mechanism for varying the degree of approach of said parts one toward the other, a contactor relatively movably supported upon one of said parts, a movably mounted actuator connected with said mechanism to effect its operation, a trip rod loosely engaged with said actuator for movement independently thereof and secured to said bed for simultaneous movement therewith, means for rigidly connecting said trip rod with said actuator, and a connection between 40 said contactor and said connecting means to effect said rigid connection.

5. In combination with the relatively movable bed and platen of a printing press including mechanism for varying the degree of approach of said members one toward the other, a contactor relatively movably supported upon one of said parts, a movably mounted actuator connected with said mechanism to effect its operation, a trip rod secured to one of said parts for movement therewith and loosely engaged with said actuator for movement independently thereof, a trip stop mounted on said actuator and adapted to engage said trip rod, and a connection between 45 said trip stop and said contactor for operation of the stop by said contactor.

6. In combination with the relatively movable bed and platen of a printing press including mechanism for varying the degree of approach of said members one toward the other, a contactor relatively movably supported on one of said parts, a movably mounted actuator connected with said mechanism to effect its operation, a trip rod secured to one of said parts for movement thereby and loosely engaged with said actuator for movement independently thereof, a trip stop spring pressed toward said trip rod and adapted to engage therewith, a latch for holding said stop from movement by said spring, and a connection between said latch and said contactor for operation of the latter by the former.

7. In combination with the relatively movable bed and platen of a printing press including mechanism for varying the degree of approach of said members one toward the other, a contactor relatively movably sup-

ported on one of said parts, a movably mounted actuator connected with said mechanism to effect its operation, a trip rod secured to one of said parts for movement therewith and loosely engaged with said actuator for movement independently thereof, a trip stop movably mounted on said actuator for engagement with said trip rod to secure the latter to the actuator, a latch adapted for engagement with said stop, an actuating rod movably mounted on said actuator and engaged with said latch to operate it, and a connection between said rod and said contactor for operation of the former by the latter.

8. In combination with the relatively movable bed and platen of a printing press including mechanism for varying the degree of approach of said parts one toward the other, a contactor relatively movably supported on one of said parts, a tripper carried by the movable support for said contactor for the operation of one by the other, a tripping tongue mounted upon a movable support for intermittent engagement with said tripper, means for effecting conditional movement of said tripping tongue and tripper each by the other but independently thereof, a connection between said tripping tongue and said mechanism for causing operation of the latter and means for disconnecting said connection to permit movement of said actuating lever independently of said mechanism.

9. In combination with the relatively movable bed and platen of a printing press together with mechanism for varying the degree of approach of said parts one toward the other, a contactor frame including a contactor pivotally supported on said platen, a tripper supported by said frame between the pivot for the latter and the contactor, a tripping tongue mounted upon a movable support for engagement with said tripper, means for effecting conditional movement of said tripper and tripping tongue each by the other but independently thereof, a connection between said tripping tongue and said mechanism for causing operation of the latter and means for disconnecting said connection to permit movement of said actuating lever independently of said mechanism.

10. In combination with the relatively movable bed and platen of a printing press, together with mechanism for varying the degree of approach of said parts one toward the other, a frame pivotally mounted on the platen and including a contactor movable by the pivotal action of the frame beyond the front edge of the platen when the latter is moved toward said bed, a connection between said mechanism and said contactor including a tripper carried by said frame, a tripping tongue mounted on a movable support, means for effecting conditional movement of said tripper and tripping tongue each by the other

but independently thereof, a connection between said movable support and said mechanism for operation of the latter by the former when an obstruction is positioned between the contactor and the movable bed and means for disconnecting said connection to permit movement of said actuating lever independently of said mechanism.

11. The combination with a printing press comprising relatively movable body and platen members, and mechanism for causing said relative movement, said mechanism including means for varying the degree of approach of said members, of a train of mechanical elements operable to actuate said means to prevent full approach of the members, a movable contactor supported by one of said members normally in an inoperative position rearwardly of the working face of said member, and cooperating devices attached to the contactor and the said train of mechanical elements and adapted to temporarily engage each other for forcing the contactor from its inoperative position into an operative position only during a portion of the approach movement of the members.

12. The combination with a printing press comprising relatively movable body and platen members, and mechanism for causing said relative movement, said mechanism including means for varying the degree of approach of said members, of a train of mechanical elements operable to actuate said means to prevent full approach of the members, a movable contactor supported by one of said members normally in an inoperative position rearwardly of the working face of said member, and cooperating devices attached to the contactor and the said train of mechanical elements and adapted to temporarily engage each other for forcing the contactor from its inoperative position into an operative position only during a portion of the approach movement of the members, one of said devices having a one way lost motion connection with the part to which it is attached to permit the devices to engage during separation of the members without moving the contactor relative to its supporting member.

13. The combination with a printing press comprising relatively movable body and platen members, and mechanism for causing said relative movement, said mechanism including means for varying the degree of approach of said members, of a train of mechanical elements operable to actuate said means to prevent full approach of the members, a movable contactor supported by one of said members normally in an inoperative position rearwardly of the working face of said member, and cooperating devices attached to the contactor and the said train of mechanical elements and adapted to temporarily engage each other for forcing the contactor from its inoperative position into an operative position only during

a portion of the approach movement of the members, the engagement of said devices causing operation of the said train of elements if an obstruction prevents movement of the contactor relative to its supporting member.

14. The combination with a printing press comprising relatively movable body and platen members, and mechanism for causing said relative movement, said mechanism including means for varying the degree of approach of said members, of a train of mechanical elements operable to actuate said means to prevent full approach of the members, a movable contactor supported by one of said members normally in an inoperative position rearwardly of the working face of said member, and cooperating devices attached to the contactor and the said train of mechanical elements and adapted to temporarily engage each other for forcing the contactor from its inoperative position into an operative position only during a portion of the approach movement of the members, the engagement of said devices causing operation of the said train of elements if an obstruction prevents movement of the contactor relative to its supporting member, one of said devices having a one way lost motion connection with the part to which it is attached to permit the devices to engage during separation of the members without moving the contactor relative to its supporting member.
